UNITED STATES PATENT OFFICE.

ADOLF ROHRBACH, CHARLOTTENBURG, GERMANY.

FLOATING TROLLEY FOR SEAPLANES.

Application filed March 20, 1924. Serial No. 700,621.

To all whom it may concern:

Be it known that I, ADOLF ROHRBACH, a citizen of the German Reich, residing at Charlottenburg, Germany, have invented 5 certain new and useful Improvements in Floating Trolleys for Seaplanes, of which the following is a specification.

Up till now, the launching and bringing ashore of seaplanes was usually effected by 10 means of inclined slipways, coupled with beach axles. With this arrangement however, the supporting contact surfaces being relatively small, the entire weight of the machine has to be carried by the bottoms of 15 floats or boats resting on the axles, or slipways respectively, so that in spite of all protecting wadding the jerks and shocks of the transportation often cause leaks in the excessively stressed floats. The floating 20 trolleys, which are slipped over the floats and attached by means of fittings, also cause frequent leakiness, as a result of the shocks, transmitted by them to the floats.

This fundamental shortcoming of all 25 types of beach axles and trolleys, known hitherto for the bringing-in of seaplanes is eliminated by the invention, described herein, by which the floats are protected from any stress produced by the wheels.

30 Several embodiments of my invention are shown on the accompanying drawings, wherein:

Fig. 1 is a front elevation of the floating trolley.

35 Fig. 2 shows a constructional detail.

Fig. 3 shows in front elevation a modified form of construction of the trolley.

Fig. 4 is a side elevation of Fig. 3.

40 Fig. 5 shows another modified design in side elevation.

Fig. 6 is a plan view of Fig. 5.

Fig. 7 shows a constructional detail.

The floats carrying the floating trolley, 45 are so arranged, that they maintain said trolley in an absolutely vertical position.

As Fig. 1 shows, the axle 1 of the wheel 2 is connected with stays 3 and 4, which are provided with telescopic extensions 5 and 6 and supported by lateral floats 7 and 8. 50 These telescopic extensions are bolted by locking devices. The entire device is fitted to corresponding plates or fittings of the seaplane. The whole locking device 9 and 10 may be substituted, as shown in Fig. 2,

55 by an automatic locking device. As shown in Fig. 2, the extensible stay 5 has an inner

tubular socket 13 in which an eccentric grip, spread out scissorlike, is arranged. One arm of this grip is being operated by a pulling device, while the other arm is hinged on 60 locking bolts, the latter being acted upon by springs in such a manner, that when sliding over apertures 17 in the stay 3, they interlock with them and thereby produce the automatic locking. 65

Instead of two floats, only one float and a watertight, pneumatic disc wheel 2 may be used, as illustrated in Figs. 3 and 4.

The device works as follows:

At a suitable place of the floating trolley, 70 a rope is attached which is cast to the occupants of the seaplane. By means of this rope the trolley is hauled up to the machine, and after having been brought into the right direction and place, is coupled by one of 75 the passengers, by means of the light extensible parts of the stays 5 and 6, to the fittings 11 and 12 of the seaplane. This coupling can safely be carried out even at a rough sea, because as long as the floating 80 trolley is being hauled up to the seaplane, the extensions of the stays remain tightly telescoped, so that even when violently in motion, they cannot strike the wings from below. With an automatic locking device, 85 the movable parts of the stays telescope into the stationary parts, after the wheel 2 has touched the landing stage, until said locking device rigidly couples the wheel axle with the seaplane. 90

A modified design is shown in Figs. 5 and 6. Both floats are combined to one single float, entirely encompassing the wheel. The wheel 2 may be elastically mounted on the float 19 by means of rubber ties 18, or the like. The stays 20 and 21 and the lateral stay 22 terminating in a ball-shaped head and turnably mounted on the fitting 23 of the floats, are attached to the seaplane. 95

In order to facilitate the detaching of the stays 20 and 21, they may each be provided with a pivoted head bolt 26, having in its upper part 27 a right-angled, oblong bolt, which after interlocking with corresponding apertures securely couples the stay by an inclination of 90°. The inclination of 90° can be given this bolt by a segment-shaped lever 27 to which pull ropes 28 or 29 are attached. 100

I claim:

1. A floating trolley for launching and bringing seaplanes ashore comprising up-

right quickly distensible supports, connections for readily attaching the upper of the extensible supports to the plane, and devices for locking the distensible supports in the 5 distended operable position.

2. A floating trolley for launching and bringing seaplanes ashore comprising upright telescopically arranged supports adapted to be distended into attachable relation with the plane and connections for readily attaching the upper support with the plane and locking the telescopically arranged supports in the distended position.

3. A floating trolley for seaplanes carrying thereon a support which is collapsible and distensible for hauling underneath the plane and ready attachment thereto during rough seas, together with connections for readily fastening the distended support to 10 the plane and means for locking the support in the distended operative position.

4. The combination of a seaplane having floatable supporting means thereunder, with a floatable trolley having a support which 15 is collapsible for hauling underneath the 20 plane and which is readily distensible into attachable relation with the plane together with connections for readily fastening the distended support to the plane and means for locking the support in the distended 25 position.

5. The combination of a seaplane having floatable supporting means thereunder with a floatable trolley carried underneath the craft to one side of the floating means and 30 having readily distensible supporting connections directly to the underside of the craft.

6. A floating trolley for launching and bringing seaplanes ashore, having supports 35 for ready attachment to the plane, a float and a trolley wheel elastically mounted thereon.

7. A floating trolley of the character set forth in claim 3 having a rigid trolley float 40 and a trolley wheel elastically mounted thereon.

In testimony whereof I affix my signature.

DR. ADOLF ROHRBACH.
